UNITED STATES PATENT OFFICE.

EPHRAIM C. SOOY, OF KANSAS CITY, MISSOURI.

BALING-PRESS.

SPECIFICATION forming part of Letters Patent No. 650,957, dated June 5, 1900.

Application filed August 28, 1899. Serial No. 728,722. (No model.)

To all whom it may concern:

Be it known that I, EPHRAIM C. SOOY, a citizen of the United States of America, residing at Kansas City, in the county of Jackson and State of Missouri, have invented certain new and useful Improvements in Bal- 5 ing-Presses; and I do hereby declare that the following is a full, clear, and exact description of the invention, such as will enable others to make and use the same, reference being had to the accompanying drawings, forming a part of this specification.

The invention has for its objects an increased development of power in the power- 15 conveying devices of the press and a reduction of power to the minimum required to operate them; second, to counteract the shock in the rebound of the head-block, and, third, the rigid connection of the suspended end of 20 the beam connecting the power with the feed-chamber of the press.

My invention consists in the novel construction and combination of parts, such as will be first fully described, and specifically 25 pointed out in the claims.

In the drawings, Figure 1 is a side elevation of the improved baling-press in an operative position with the sides of the feed and baling chambers removed. Fig. 2 is a plan view with the sweep and hopper removed. Fig. 3 is an isometrical view of the bottom of the feed-chamber of the press, showing the suspended end of the main beam extending from the power mechanism in rigid 30 connection with the feed-chamber. Fig. 4 is a detail view of the base-plate at the power end of the press, showing the bed for the vibrating rope-operating plate and the eccentric position of the crank-shaft bearing, also showing the lateral extension of the base-plate and the vibrating plate in dotted lines. Fig. 5 is a plan view of the baling and feed 35 chambers of the press as seen in Fig. 1, and showing a modified form of power with a rod-and-chain connection. Figs. 6 and 7 are plan and side views, respectively, of an alternate construction of the power mechanism of the press.

Referring to the drawings, A represents 40 the feed-chamber of the press, and B the baling-chamber, which are of ordinary construction. In the feed-chamber A is the

head-block C, which is also of well-known construction. The baling-chamber B is mounted upon the axle d, upon the ends of 55 which axle are the wheels D D. With the axle d are pivotally-connected one end of the parallel bars d' d', the other ends of which bars are extended rearwardly and to a position near the rear end of the feed-chamber A. 60

E is a knuckle-jointed lever operating the head block C. One portion or arm of the lever E is triangular in form, the sides e' e' of which are connected at their lower ends pivotally to a shaft e², which extends transversely to the feed-chamber A and is arranged a short distance above the bottom and near the rear end of said bottom. The other portion e or arm of the lever is pivotally connected with the head-block C at c'. Said portion of the lever from the pivotal point of the lever with the head-block to its pivotal connection with the upper meeting ends of the parts e' e' is forked at c². Within the inner portion of the sides a' a' of the feed-chamber 75 A, and near the bottom a and a short distance forward of shaft e², are secured grooved blocks F, in the groove of which are yielding strips f, such as wood or rubber, against which the rear end of the head-block comes 80 in contact at the limit of rebound of the head-block.

G represents the power mechanism of the baling-press, which is constructed as follows: With the axle i supporting the power mechanism is connected rigidly a circular plate h, upon which is an upwardly-extended annular flange h'. Within the flange h' is a circular plate h², fitting therein, so as to permit an oscillating movement of the axle i. With the top of plate h² is rigidly connected a rectangular-shaped base or casing h³, with the forward end of which is connected the lower end of the upwardly and rearwardly extended casting or gooseneck h⁴, which is deflected 85 or inclined laterally at an angle to the base-plate h³, in the end of which is the shaft-bearing h⁵, which receives the upper end of shaft g². In the outer end of the base-plate 90 h³, beneath the bearing h⁵ and near one side of said plate h³, is a journal-box h⁶, which receives the lower end of shaft g². Upon the surface of the base-plate h³ a short distance from the journal-box h⁶ and in the di- 95 100

rection of the casting h^4 and equidistant from the longitudinal edges of the plate h^3 is a stud h^7 , upon which is pivoted the vibrating segment-plate g . Upon the edge of the base-plate h^3 is a lateral extension of said base, consisting of a bar h^8 , bent in the arc of a circle to afford a bearing for the segment-plate g , and the ends of said bar bent upon the line of the chord of arcs, as at h^9 h^{10} , and said ends bolted to the said base-plate, the upper edge of the bar h^8 being in the horizontal plane of the upper surface of the base-plate. Upon the stud h^7 is pivoted the vibrating lever g , which consists of a flat plate 15 in the form of a segment of a circle, which is pivotally connected with the stud h^7 on base h^3 and secured on said stud by the screw-cap h^{11} . In the outer curved edge of the plate g is a groove g' , which receives and guides the 20 rope N in the movement of said plate upon its pivot. In the bearings h^5 on the casting h^4 , and the journal-box h^6 on base h^3 , is a vertical shaft g^2 , upon which are the crank-arms g^3 g^4 g^5 . With the side of the crank-arms at 25 their outer end are connected by bolts g^6 the blocks g^7 , curved upon their outer and inner faces and fitting the curved outer end g^8 of the said arms, the lower end of which blocks extend downwardly nearly to the plane of 30 the surface of the plate g in the circle of rotation of the crank-arms.

Upon the radial line of the segment-plate g , toward the casting h^4 , is a notch g^{12} to admit a portion of the side of the casting. Upon 35 the other radial line of said plate g and upon the edge of the plate described by said line is an upwardly-extended flange or plate g^9 , which extends from a point near the pivotal point of said plate with the stud h^7 to a position a short distance from the outer curved 40 edge of said plate g , the inner edge g^{10} of which flange is in the path of and is met by the curved surface and lower end portion of the block g^4 on the crank-arm g^3 in the circle of 45 rotation of said arms, and said inner edge g^{10} is inclined inwardly at an angle to the radial line of the inner edge of the plate g to which it is attached, the rear edge portion at the outer end of said flange being curved, as at g^{11} .

50 While exerting power, the crank-arms are enabled by the inclined edge g^{10} to obtain an accelerated movement with an increase of power. With the upper end of the shaft g^2 is connected a sweep K in the ordinary manner for the operating of the power mechanism by horse-power.

55 L represents the main connecting-beam, one end of which is connected with the portion of the base-plate h^3 supporting the casting h^4 by the plates l^1 , secured to the outer longitudinal edges of said beam and the base-plate. The other end of beam L extends to a position beneath the feed-chamber A of the press and is connected pivotally with the 60 outer ends of the parallel bars d' on the axle d by means of a bolt l^2 , so as to be lowered in position in line with the power end of the

press and the thrust thereof resisted by the said bars d' and the rear axle of the baling-chamber. The said end of the beam L is held 70 in a suspended position from the ground by the supporting-plates M M , which are pivotally connected with the under side of the bottom a of the feed-chamber A , and also with the longitudinal edges of beam L a short distance 75 in rear of the point of connection of the parallel bars d' with said beam l^2 l^2 are eyes upon the edges of the beam L a short distance from the pivotal connection of the plates M with said beam and in the direction of the 80 end of said beam connected with the power.

With the vibrating plate or segment g is connected one end of a wire rope or cable N , which end extends within the groove g' of said plate g , the extreme end being secured 85 by a block g^6 , bolted to the edge of said plate having the flange g^6 and to the outer side of said flange. The other end of the wire cable extends to the under side of the feed-chamber A and thence over a grooved guide-roller n 90 on the under side of said chamber, thence through a suitable opening in the bottom of said chamber upwardly between the forked ends of the parts e^3 of the knuckle-jointed lever E , thence over the upper end of said 95 lever and within the curved extensions e^4 on the upper end of said portion e^1 of said lever. In the curved extensions e^4 is a clamping-plate e^5 and a bolt e^6 .

g^{12} is a brace connecting the casting g^4 with 100 the beam L .

To assist in the rebound of the head-block C , a spiral spring O is arranged beneath the baling-chamber B and secured at one end adjustably to a screw-bolt o , extending through 105 the lug o' , secured to the under side of chamber B , and upon which bolt is a nut o^2 . With the other end of the spring O is connected one end of a rope o^3 , the other end of which rope extends over a pulley o^4 at the rear end 110 of the feed-chamber A , thence extended within said chamber and connected with a plate o^5 on the lower rear end of the head-block C .

In the operation of the press the material 115 to be baled is supplied to the hopper a and the feed-chamber A . Power is then applied to the sweep K and the shaft g^2 caused to rotate in its bearings. In the rotation of the shaft g^2 the block g^4 on one of the crank-arms 120 g^3 comes into contact with the inner edge g^7 of the flange g^6 and in one-quarter of a circle in rotation moves over the said inclined edge g^{10} , causing the plate g to move in the same direction and a corresponding distance. In 125 the same movement tension is applied to the rope N and the power applied to the knuckle-jointed lever E , drawing the knuckle-joint downwardly and forcing the head-block C within the baling-chamber B and the material to be baled, which material is at once compressed. As soon as the crank-arm g^3 reaches a position as seen in dotted lines in Fig. 2, or nearly above the plane of the base- 130

plate h^3 , the block g^4 passes the outer end of the flange g^6 and releases the tension upon the rope N . At the same time the expansion of the baling material after compression causes the head-block or plunger to rebound with great violence, taking up the rope made slack by the release of the vibrating plate g and drawing said plate into the position as shown in full lines in Fig. 2 in readiness for the contact of another crank-arm. In the forward movement of the head-block to compress the material the rope o^3 is drawn by the head-block over the pulley o^4 , lengthening the spring O , and upon the rebound of the head-block the spring contracts, assisting the rebound in the initial compression of the material or before a bale has been formed in the baling-chamber, after which time the expansion of the baled material is sufficient to cause the rebound of the head-block. In such rebound the head-block comes in contact with the yielding strip f in the block F in the inner side of the feed-chamber A and the shock to the plunger and press materially lessened.

In the eccentric position of the crank-shaft to that described by the stud h^7 on the base-plate h^8 a greater power is conserved, the effect being to gradually increase the power exerted by the crank-arms on the vibrating plate g and lessen at the same time the power required to operate the crank-shaft. In this respect the team, while exerting the necessary power upon the sweep to compress the material, is not caused to exercise greater exertion to force the head-block to its full extent within the baling-chamber. The blocks g^4 are preferably chilled steel and may be renewed.

In moving the press from one location to another the bar d' , which receives the thrust of the beam L in the operation of the press, is disconnected and the beam moved forwardly as far as the guide-plates M permit and upwardly against the under side of the feed-chamber, and a bolt inserted through the bottom a of said chamber and the beam L , and a nut placed upon said bolt, as seen in Fig. 3, which makes a rigid connection with the baling-chamber, it being observed that the wheels II , which support the power mechanism, are lower in position than the wheels $D D$ during the operation of the press, so as to bring the beam L close to the ground, as seen in the drawings, and for this purpose the wheels II may be removed from the axle or the ground excavated the proper depth.

Instead of employing wire rope N the rod P may be substituted. For this purpose the change in the power mechanism is simply in the substitution of the outwardly-extended plate R , as seen in Fig. 6, for the vibrating segment g , as in Fig. 1. The plate R is similar in construction to one of the crank-arms g^3 and is pivotally connected with a stud on the base-plate, as described, of the segment-plate g . The plate R is provided with a re-

cessed inner edge r , which extends horizontally through the end of the plate-arm R , and in the end of the said arm is a rotary pivot r' , through which pivot passes one end of rod P , operating the knuckle-jointed lever E , which end is threaded and provided with a nut r^2 . The recessed inner edge permits said rod P to come nearly into a parallel position with the plate R in a retracted position of the rod P .

Instead of the blocks g^4 upon the ends of the crank-arms the antifriction-rollers r^3 are employed, which are pivotally connected with the under side of said arms and come in contact with the inner edge of an upwardly-extended flange r^4 , which is the same as the flange g^6 on the segment-plate g , the said rollers bearing upon the inner edge of said flange r^4 and passing therefrom when the crank-arm and rod P are in the position seen in dotted lines in Fig. 5. Upon the other end of rod P , which extends to a position near the rear end of the baling-chamber, is a chain p , which extends over the knuckle-jointed lever E in the same manner as described of the rope N .

In Figs. 6 and 7 the construction is varied in the power from that seen in Fig. 1. In these figures S represents the gooseneck-casting, and s the vertical power-shaft journaled thereon at one end and in the base-plate s^2 at the other end. Upon the shafts s are segment-gears s^3 in place of the crank-shafts. The vertically-arranged vibrating segment-plate s^4 is pivotally connected with a journal-bearing s^5 on the side of the gooseneck-casting, the collar s^6 upon which plate is held upon the journal by the caps s^7 , in which is a screw s^8 , extending within the end of the journal-bearing. Upon the face of the segment-plate is bevel-gear s^9 , with which gear the segment-gear on the shaft S engages intermittently. The rope s^{10} is connected with the segment-plate s^4 in the same manner as in plate g in Fig. 1, the said plate also being grooved to receive the rope s^{10} . In this construction as the power is applied to the rope s^{10} from the segment-plate s^4 the tension is maintained in a direct line with the main beam, connecting the power with the baling devices. The power from the beam is applied to shaft s in the same manner as indicated in Fig. 1.

I am aware that flanges in the arc of a circle and also radial flanges with curved edges have been employed, against which the rollers upon the crank-arms are caused to come into contact and impart power to operate the head-block, none of which enable the application of power in an increasing ratio, as in my invention.

Having fully described my invention, what I now claim as new, and desire to secure by Letters Patent, is—

1. The combination in a baling-press with a suitable base-plate and with the upwardly and rearwardly extended shaft-bearings for the driving-shaft, of the driving-shaft and

power-arms extending outwardly therefrom, a stud upon the base-plate, a vibrating segment-plate upon said stud and an upwardly-extended radial flange upon said plate having the plane of its bearing-face passing to one side of the axis of the plate, and antifriction devices upon said power-arms adapted to contact with said flange and to be disengaged therefrom intermittently, means substantially as described for rotating said driving-shaft and power-conveying devices connecting said segment-plate with the material-compressing devices of the press.

2. In a baling-press the combination with the chamber having the material-compressing devices and with the power-actuating mechanism of a beam connected at one end with the said mechanism and pivoted supporting-plates therefor at the other end, bars pivotally connected to the rear axle and to said beam and means for permitting said beam to be clamped directly to the baling-chamber.

3. In power mechanism for baling-presses,

the combination with a suitable base-plate, and with the outwardly and rearwardly extended neck-plate inclined laterally at an angle to said plate, of a rotary shaft journaled in said head-plate and said base-plate, a stud upon said base-plate, a vibrating segment-plate pivotally connected with said stud and having a groove in its outer curved edge, an upwardly-extended flange upon said segment-plate, having the plane of its bearing-face passing to one side of the axis of the plate, power-arms upon and extending outwardly from the rotary shaft, and antifriction-blocks detachably connected with said arms, extending downwardly and adapted to come into contact with the bearing-face of said flange, and a cable having suitable connection with said segment-plate within the groove in said plate, and means for rotating said shaft.

EPHRAIM C. SOOY.
